UNITED STATES PATENT OFFICE.

ROBERT Y. BRADSHAW, OF CHICAGO, ILLINOIS.

MACHINE FOR CLOSING AND SEALING THE ENDS OF PAPER BOXES.

No. 902,273.

Specification of Letters Patent.

Patented Oct. 27, 1908.

Application filed November 1, 1906. Serial No. 341,613.

To all whom it may concern:

Be it known that I, ROBERT Y. BRADSHAW, a citizen of the United States, residing at Chicago, in the county of Cook and State of Illinois, have invented certain new and useful Improvements in Machines for Closing and Sealing the Ends of Paper Boxes, of which the following is a full, clear, and exact specification.

10 My invention relates to improvements in machines adapted to close and glue or cement the ends of paper boxes or cartons and has for its object to provide mechanism adapted to perform the indicated work efficiently and 15 with a satisfactory degree of speed.

A further object is to provide improved mechanism that may be readily adjusted and adapted to receive interchangeable parts for 20 operating on various sizes of boxes or cartons and for performing the operations of closing and sealing both bottoms and tops of cartons on the same machine.

To the attainment of these ends and the accomplishment of other new and useful objects, as will appear, the invention consists in the features of novelty in the combination and arrangement of the several parts, herein-after more fully described and claimed and shown in the accompanying drawings, illustrating 30 an exemplification of this invention, and in which:—

Figure 1 is a view in side elevation of the machine and Fig. 2 is a plan view of the same. Fig. 3 is a vertical sectional view on line 3—3, Fig. 1. Fig. 4 is a perspective view of a small section of endless carrying belt employed for conveying the boxes or cartons in order to present them to the various mechanisms for successive operations. 40 This view illustrates one of the carton holders or retainers employed when it is desired to fold and seal the first end or bottom of the box before the insertion of the filling material and subsequent folding and closing of the top 45 of the same. Fig. 5 is a perspective view of the holder attached to the endless carrier of the type employed in folding and sealing the top members of the box subsequent to the folding and sealing of the bottom members 50 and usually after the filling material has been inserted. Fig. 6 is a vertical sectional view on line 6—6, Fig. 5. This view shows the box or carton inserted in holder and the 55 relative positions of the top folding members of the carton before being operated on by the mechanism. Fig. 7 is a broken sectional

view of the endless carrier construction taken on line 7—7, Fig. 4. Figs. 8, 9, 10, 11, 12, 13 and 14 are perspective views of the boxes or cartons illustrating the various 60 actions of the mechanism in folding the front and back flaps, gumming the two sides of one of the side flaps and the subsequent operation of closing and sealing both side flaps. Fig. 15 is an enlarged detail plan view of the 65 mechanism adjacent to the receiving and delivery end of the machine and illustrates particularly the mechanism adapted to enter the path of the moving carton and fold the first end flap. Stationary mechanism inter- 70 posed in the path of the carton for folding the forward end flap is also shown in this view. Fig. 16 is a vertical sectional view on line 16—16, Fig. 15. Fig. 17 is a detail sectional view on line 17—17, Fig. 16. Fig. 18 is an 75 enlarged detail view in elevation partly in section illustrating the mechanism shown also in Fig. 15 adapted to lie in the path of the carton and fold the forward end flap. This view also illustrates in detail the construc- 80 tion of the apparatus adapted to apply the glue or sealing material to both sides of one of the side flaps. Parts of the gluing apparatus are broken away to show the construction. Fig. 19 is a broken detail view of a 85 part of the gluing apparatus. Fig. 20 is an enlarged detail view in elevation of that portion of the mechanism which acts on the carton immediately after it is carried from the gluing mechanism. Fig. 21 is a vertical sec- 90 tional view on line 21—21, Fig. 20. Fig. 22 is a sectional view on line 22—22, Fig. 21. Fig. 23 is a sectional view on line 23—23, Fig. 21. Fig. 24 is an enlarged broken view in side elevation of the mechanism adapted 95 to fold the final side flap and to retain all of the flaps in position under pressure for an interval of time in order to allow the sealing material to act. Fig. 25 is a detail sectional view on line 25—25, Fig. 24. Fig. 26 is a 100 sectional view taken laterally across the path of the conveyer and showing substantially the mechanism illustrated in Fig. 24, in elevation. This view also illustrates the movement of the spring controlled presser 105 member in folding and holding the final side flap onto the previously gummed side flap of the carton. Fig. 27 is a diagrammatic plan view of that portion of the mechanism shown in Figs. 24 and 26 which is interposed in the 110 path of the conveyer and trips the spring controlled presser member by throwing the

same over center. Fig. 28 is an enlarged detail view in side elevation of the mechanism adjacent to the discharge cam track which releases and discharges the completed carton 5 from the machine. Fig. 29 is a view on line 29—29, Fig. 28. Fig. 30 is a view on line 30—30, Fig. 29.

The mechanism is carried by main frame 1 which may be provided with suitable supports or legs 2. The frame is adapted to carry endless belt 3 mounted on driving sprockets or pulleys 4 and driven sprocket 5 all of which are journaled to rotate on main frame 1. Power for operating machine is supplied by belt receiving pulley or wheel 6 mounted on shaft 7 which carries the driving sprockets 4. Endless belt 3 may be of any desirable construction but the form shown in Fig. 4 is preferred, which consists of a common form of sprocket chains the two plies or strands of which are united by members or frames 8 at frequent intervals. In order that the joinings of the chains with members 8 may be flexible, suitable pins or screws 3^a may be passed through the chains and screw threaded into, or otherwise attached to 8. Members 8 are adapted to carry the holders for boxes or cartons and are also adapted to carry spring controlled mechanism for the folding of final flap and for discharging the completed carton. Member 9, Fig. 4 is a form of holder that is adapted to hold the carton during the first operation of folding and sealing. The carton as it appears ready for insertion on the holder 9, is illustrated in Fig. 8. The holder 9 is provided with supporting branches 9^a and 9^b at its base by which it is adapted to be attached to member 8. Slots 10 are provided in order that these holding members may be mounted on endless belt for adjustment and suitable means are provided by which they may be readily attached and detached to the carrier belt for the purpose to be hereinafter described.

Member 12 (see Fig. 5) illustrates a form of holder for attachment on endless carrier belt adapted to receive box or carton for the final folding operation which consists in folding and sealing the top end thereof, generally, after the carton has received its filling. Like holder 9 the member 12 is provided with branch members 12^a and 12^b at its base for attachment to endless carrier belt. It is preferred that the base members 12^a and 12^b are constructed like the base members 9^a and 9^b of holder 9, thus adapting both holders to be perfectly interchangeable. The utility of this construction is evident when it is understood that carrier belt may be provided entirely with holders 9 in order to fold the first end of empty cartons. Holders 9 may then be removed and the filled carton holders 12 inserted which will permit the machine being run indefinitely for sealing or closing the last end of the carton, or, if desirable this carrier

belt may be extended a considerable distance so that a large number of holders may be carried and the holders may be distributed on carrier belt in any desired arrangement. The carton or box as it appears in Fig. 8 when inserted on member 9 protrudes above the top thereof only the distance that the carton may be slotted for the purpose of forming the flaps at one end. When the flaps at one end of the carton are folded, it is shortened and in order to allow for this difference in length holder 12 is provided with abutting members 13 on the inner side adapted to support the carton in the manner illustrated in Fig. 6, in which the carton is indicated by the numeral 14.

15 is a slot in the opposite sides of holder 12 adapted to permit movement of discharge finger 16 therein for the purpose of discharging completely sealed cartons from the 85 holder. Discharge finger 16 is also used on conveyer when holders 9 are in position. The form of holder 9 permits the necessary movement of 16 enabling the carton to be discharged therefrom in the condition illustrated by Fig. 13.

In order that the operation of the mechanism may be more thoroughly understood the operations performed on a carton, as illustrated in Fig. 8 and subsequent figures resulting in the carton closed at one end, Fig. 13, will now be described: In the various illustrations of the mechanism holders of the type indicated by 9, Fig. 4, have been used throughout. The position of the holder to receive the carton to be folded is illustrated by the upper case letter A appearing on holder 9, Figs. 1, 2 and 15. 14 indicates the body of the carton. 17, 18, 19 and 20 indicate the flaps to be folded. The carton after insertion on frame 9 moves in the direction taken by the arrows, Figs. 2 and 8, and for convenience in the description, 17 and 19 will be hereinafter referred to as rear and front flaps, respectively, and 18 and 20 as side flaps.

The position of the holder A^o in relation to its adjacent parts is shown more nearly correct in Figs. 1 and 15 than in Fig. 2. In order that rear end flap 17 may be folded in the manner indicated in Fig. 9, vertical support 21 is rotatably mounted on frame members 1 in any convenient manner as for example, elongated U shaped member 22 provided with bearings 23 and 24. Member 21 is held in position by collars 25 and 26 on upper and lower sides of bearing 23; adjustable set screw 27 in 26 serves as a means of adjustment and also acts as a stop to limit the rotation of 21 by contacting with stud 28 mounted on bearing 23. 21 is provided with fixed arm 29 and also with fixed folding finger 30. Member 30 is provided with hooked end 30^a which part is adapted to contact with flap 17 which it does by overtaking the carton due to

the accelerated movement imparted to it by rotation of shaft 21 through the contact of fixed arm 29 with the upwardly extending lug 31 formed on endless belt or carrier adjacent to member 9. It will be noted that this lug is also provided with a recessed portion 31^a for a purpose hereinafter described. It will be noted that the position of lug 31 is such that it contacts with arm 29 and starts the rotation of shaft 21 before the carton has reached a point opposite 21. The arm 30 being longer than lever 29 causes the folding finger 30^a to travel faster than the carrier and consequently to overtake the carton and fold the flap 17 to the position indicated in Fig. 9. Folding finger 30 may be adjustably mounted on 21, a convenient form being member 32 to which it is attached and which is journaled on 21 and adjustable in relation thereto by means of set screw 33. Folding finger 30 is held normally out of the path of carrier belt by spring 34 which is interposed between bracket 22 and member 21 by means of collar 25. Contact of lug 31 with fixed arm 39 rotates shaft 21 and torsional spring 34 which returns 21 to normal position when lug 31 has passed out of contact with 29.

Immediately after folding finger 30 has reached the approximate position indicated by dotted lines, Fig. 15, but before it has returned to normal position the front end flap 19 is brought in contact with stationary folding member 36. It will be noted that member 36 is provided with branch 36^a so shaped that it does not contact with side flap 18 but presents a beveled or cam surface 36^b to flap 20. As the carton moves forward member 36 folds flap 19 in manner indicated in Fig. 10 and at the same time exerting pressure outwardly by reason of its beveled surface folds flap 20 outwardly approximately at right angles to the side of the carton as indicated in Fig. 10 thus preparing flap 20 to enter gumming or gluing apparatus. It will be noted that before member 36 has entirely closed flap 19 the action of lug 31 on the carrier has released arm 29 and permitted folding finger 30 to return to normal position.

50 The gumming or gluing apparatus is supported by suitable bracket 37 mounted on frame members 1 which bracket also carries stationary folding member 36 and its branches. The apparatus employed for distributing glue or gum consists of upper and lower feeding members 38 and 39; the lower member 39 is fixed in support 37 and is surrounded by the overflow trough or cavity 40 provided with outlet 41 for conducting away such of the liquid glue or gum as may not be needed.

42 is a tank or receptacle preferably mounted somewhat above the level of the gum distributing apparatus. Suitable conduits 43 and 44 convey the gumming mate-

rial to distributing apparatus. Lower feeding member 39 is provided with inlet channel 45 and an inner receptacle or chamber 46 adapted to retain a quantity of gumming material. The upper distributing member 70 75 38 is shaped similarly to member 39 having an interior receptacle or chamber 47. Member 38, however, receives the gumming material through its inlet tube 44 at its side, (see Fig. 3). The stem 38^a is mounted in frame member 37 to have a vertical movement and may be fitted with threaded adjusting screw 48 for adjusting it in relation to frame 37 and in relation to lower feeding member 39. Folding member 36 presses flap 20 outwardly as indicated in Fig. 10 and this flap is moved forwardly along the under edge of branch 36^b until it enters the slot 49 between gumming feed members 38 and 39. It will be noted that these members (see Fig. 85 3), are approximately the width of the holder 9 and consequently the width of flap 20. The liquid gumming substance finds its way from the inner receptacles 46 and 47 through elongated slots 50 and 51 into the interval 90 or space between 38 and 39. As flap 20 passes through this space it contacts with both 38 and 39 thoroughly covering both sides or surfaces of it with gumming material as indicated by 20^a and 20^b, Figs. 10, 11 95 and 12. Feeding members 38 and 39 are provided with elastic scraper members 52 and 53. These members are also approximately of the width of the flap and as it passes there-between any superfluous deposit of the gum 100 substance is removed from the flap and finds its way into receptacle 53^a and thence into the overflow receptacle 40 and through discharge outlet 41 and its communicating tube 41^a. In this construction of the gumming 105 apparatus feed members 38 and 39 are mounted in holding frame 37 in such a manner that they are readily removed by simply disconnecting conduits or tube 43 and 44 and lifting them out of their sockets. This 110 construction is very convenient on account of the necessity for frequently removing the parts and thoroughly washing and soaking them, which may be done at all times when the machine is not in use.

115 After flap 20 is carried past the gumming mechanism and is disengaged from the scraper members 52 and 53 it is free to assume its original position which it does by reason of the elasticity of the material, as indicated in Fig. 11, in which it is shown almost in the same plane as the side of the box or carton 14 and to which it is integrally attached. It will be noted that the stationary rod 36^a is continued in the path of the moving carton thus serving to hold members 17 120 and 19 continuously in folded position as indicated in Figs. 10 and 11. After the carton is freed from the gumming apparatus in its 125 onward movement, an interval of time is al- 130

4

lowed for flap 20 to assume its said original position after which the carton reaches its position to be operated upon by folding finger 54 which is designed to fold flap 20 inwardly and upon front and rear flaps 17 and 19. It will be noted that by gumming both sides of flap 20 flaps 18 and 17 will be secured in position when flap 20 is pressed inwardly and downwardly and its surface 20^a unites with flap 19, its upward gummed surface 20^b serving to unite with the under surface of flap 18 when this flap is folded inwardly and upon the surface 20^b of flap 20 as indicated in Fig. 13. Folding finger 54 is carried by upright supporting member 55 which is mounted to slide in a direction approximately parallel with the line of the forward travel of the endless carrier belt. In order to secure this movement 55 is mounted on member 56 which is journaled to slide on member 57.

In order to adjust finger 54 it is preferably mounted in sliding collar 58 and provided with adjusting thumb nut or screw 59. Slide supporting rod 57 is attached in any convenient manner to frame 1. Sliding member 56 is held normally in operative position as illustrated in Fig. 20 by means of tension spring 60 connected thereto at one end and the other end to the main frame or suitable bracket mounted thereon, as 61. Finger 54 and its supporting mechanism is carried forward with each carton while it is acting thereupon to fold inwardly flap 20. This movement is accomplished by means of pawl 62 loosely mounted in member 56, and adapted to be held in its normal position by gravity and capable of being rotated in a plane perpendicular to the line of forward movement of member 56 as it slides on 57. Pawl 62 is engaged by lug 31 on the carrier which causes member 56 to be carried forward in the direction of movement of the carrier on support 57. Finger support 55 is provided at its base with an arm 63 adapted to contact with the upper surface 64^a of cam 64. As the parts move forward finger 54 is moved into the path of the carton by the mechanism just described and folds flap 20 inwardly in the manner indicated in Figs. 12, 21 and 26. It will be noted that just prior to the final folding of flap 20 on the top of flap 19 stationary holding rod 36^a is discontinued. As folding finger 54 is carried forwardly it is ultimately permitted to return to normal position in the following manner: When arm 63 passes beyond the rear end of cam track 64^a it contacts with the under surface of 65 and is forced downwardly and below the plane of cam 64. After arm 63 has passed beyond cam 64 pawl 62 is disengaged from lug 31 by reason of inclined surface 66 with which it is brought into contact. Being thus freed mechanism carried by member 56 is returned by spring 60 to normal position. Arm 63 is carried rearwardly past cam 64 by passing on

the under side of it. 64 is also pivotally mounted at 67 on supporting member 68 which is carried by the main frame. It is held within the limits of its downward movement by lug or pin 69 operating in slide 70 and is held in its normal position by means of spring 71. This construction permits an upward movement of track 64 to permit lever 63 to pass beyond it in returning to normal. In order to protect the parts from undue strain in returning to normal, elastic means, as buffer spring 72, may be provided.

It should be noted that the action of folding finger on flap 20 is not sufficient to cause it to remain in folded position and consequently before it is returned to normal, as just described, final folding and compressing member 73 is operated into the path of the carton to fold flap 18 inwardly and over the top surface of flap 20^b. The first movement of folding member 73 is illustrated by dotted lines in Fig. 26. This movement has the effect of folding flap 18 forwardly at an angle sufficient to retain flap 20 in position immediately after which finger 54 is returned to normal. Folding and compressing member 73 is pivotally mounted on member 74 which is slidably mounted on supporting standard 75 carried by frame 8. Member 74 as mounted on 75 is limited in its vertical movement on standard 75 by means of adjustable supporting clamp 76 rigidly attached to 75. Downwardly extending arm 76^a is provided with slot 76^b which takes 74^a on member 74 and permits the limited vertical movement just referred to, thus preventing a rotary movement on support 75 of part 74 and folding member 73. Supporting member 74 is provided with a depending arm 74^b. Folding and compressing member 73 is held in its normal vertical position away from the top of the carton support and is also held firmly in position on top of the folding flap of the carton by means of spring 77 connected to lug or arm 73^b and to the lower end of depending arm 74^b at 74^c.

78 designates the point of pivotal connection of folding and compressing member 73 to its supporting member 74. By reference to the illustrations it will be seen that when member 73 is in its normal vertical position out of the path of carrier belt spring 77 operates to lock 73 in such vertical position by reason of the pivotal point 78 having passed beyond the line of connecting points of attachment of the spring 73^b and 74^c. On the other hand when 73 is depressed and brought into position on top of the carton the line connecting the points of attachment with the spring passes on the other side of the pivotal point and holds the member firmly in position. It will be noted that sliding member 74 normally rests by reason of gravity in the position indicated by reference to parts in Fig. 26, in which pin 74^a is shown in the lower

limits of slot 76^b. This construction leaves flap 73 free to contact with the top of the carton and when the movement of the member carries the line connecting the points of attachment of the spring out of its normal position and beyond pivotal point 78 the pulling action of the spring exerted between member 73 and depending member 74^b acting on the top of the carton as a fulcrum will raise the entire mechanism and slide member 74 on upright support 75 until the pressing surface of 73 conforms to the top of the carton.

It has been observed that spring 77 holds folding and compressing member 73 normally in vertical position and away from the top of the carton. In order to bring member 73 into action suitable mechanism is mounted on the main frame of the machine by means of upright member 79 consisting of cam track 80 and lever 81 pivotally mounted to move in horizontal plane. The action of member 81 in starting the movement of folding and compressing member 73 is best observed by reference to diagrammatic view in Fig. 27. Support 75 is brought in contact with end of 81 and as it moves forwardly in the direction of travel of the endless carrier the outer end of the lever is brought in contact with 73. The forward movement of the mechanism pushes 73 toward the top of the carton until the action of spring 78 having passed beyond center acts to depress 73.

82 is the pivotal connection of lever 81. 81^a is a branch which contacts with support 79 to prevent further rotation on pivot 82 when lever 81 assumes its normal position. 81 is held normally in position illustrated in Fig. 27 by the torsional spring 83 acting between it and support 79. Member 73 is provided with a depending arm 73^b and may have an antifriction roller 73^c mounted thereon. The action just described of lever 81 operates to bring roller 73^c in contact with the cam surface of track 80. The action of spring 78 depresses 73 until roller 73^c is brought into firm contact with the surface of 80, which surface is inclined upwardly thus gradually permitting the flap 73 to be brought into firm holding position on the top of the carton.

When the mechanism has carried roller 73^c beyond the limits of cam track 80 the folding and compressing of the flaps is complete but it yet remains for member 73 to continue in contact with the folding flaps for a sufficient time to insure that the gumming substance has acted to hold them permanently. This is accomplished by permitting member 73 to continue in its folded position while the carton carrying mechanism is carried over driving pulleys 4 and around the under side of the machine until the carton has almost reached the opposite end when roller 73^c is brought in contact with cam track 83. The upward

inclination of this track acting on roller 73^c releases holding member 73 from the top of the carton and causes it to assume its normal position (see Figs. 28 and 29). The carton is now ready to be discharged from the mechanism which is accomplished by movement of discharge finger 16. This finger is carried by member 84 mounted to slide on support 75. 84 is provided with a laterally extending arm 84^a. Finger 16 thus carried is adapted to remain in contact with frame 8 while carried on the upper ply of the endless conveyer. Supporting member 84 is preferably made of solid metal and given sufficient weight to cause it to exert some pressure through finger 16 in crowding the carton off holder 9 at the proper time. When the carton carrying mechanism passes over driving sprocket 4, arm 84^a contacts with track 85 on the lower side of the main frame. By referring to drawing Fig. 1 it will be noted that track 85 is continued until the mechanism has moved past cam track 83 where folding and compressing member 73 is removed from the top of the carton. When the rear end 90 85^a of this track is reached, finger 16 being no longer supported by lug 84^a, drops downward within the limits of its movement and crowds the carton off holder 9 where it may be received in any convenient receptacle or carrier.

In order that upright supports 75 may be strengthened during the moment antifriction wheels 73^c contact with cam tracks 80 and 83 longitudinally extending supporting members 86 and 87 may be provided behind which the outer extremities 75^a of these members may pass during the time that the cam tracks are exerting pressure on roller 73^c. The auxiliary standard 88 which is mounted on member 8 adjacent to support 75 serves also to support 75 since members 74 and 84 are journaled to slide on it and are thereby held against torsional strains.

In order that the invention might be fully understood, the details of an embodiment thereof have been thus specifically described, but

What I claim is:—

1. In a device of the character described, the combination of conveyer mechanism adapted to move in a predetermined path, means carried by said conveyer mechanism for holding a box or carton having side and end flaps adapted to be folded and sealed, a folding finger mounted on said main frame and adapted to be moved into the path of said conveyer by the forward advance of the conveyer, said finger operating to enter the path of movement of a carton from the rear and to overtake and fold the rear end flap forwardly and inwardly, a member carried by said main frame in the path of said conveyer adapted to contact with the forward end flap of a carton, means in the path of said

conveyer adapted to apply an adhesive to one of said side flaps and means on said conveyer adapted to fold said side flaps inwardly and to retain them in folded position during a 5 predetermined part of the movement of said conveyer.

2. In a device of the character described, the combination of a main frame, a conveyer mechanism, means on the conveyer mechanism adapted to support a box or carton during a predetermined period of travel of the conveyer, means for folding and gumming the ends of the boxes or cartons carried on the conveyer, a member carried on said 10 conveyer adjacent the carton support, a discharge finger on said member, and a track or way on the main frame adapted to control the movements of the member and the discharge finger carried thereby.
- 15 3. In a device of the character described, the combination of conveyer mechanism adapted to travel along a predetermined path, box or carton holding means carried thereby, said means adapted to receive a box 20 or carton provided with side flaps and end flaps to be folded for the purpose of forming a top and bottom therefor, means for actuating said conveyer mechanism, means in the path thereof adapted to fold the front and 25 rear end flaps of a box or carton carried thereby, means adjacent to the path of movement of said conveyer mechanism adapted to apply an adhesive to the two sides of one of the side flaps of said box or carton, means 30 interposed in the path of forward movement of said conveyer mechanism adapted to be actuated thereby for folding inwardly said gummed side flap, and means carried by said conveyer mechanism adjacent to said box or 35 carton holding means adapted to fold the remaining side flap of said box or carton, said last mentioned means adapted also to remain in contact with the folded flaps of said carton during a predetermined portion of 40 45 the forward travel of said conveyer mechanism.

4. In a device of the character described, the combination of conveyer mechanism adapted to move along a predetermined path, embodying means for carrying boxes or cartons provided with side and end flaps adapted to be folded and sealed for forming tops or bottoms therefor, means for actuating said conveyer mechanism, and means 50 55 interposed in the path of said conveyer mechanism adapted to apply an adhesive to one of the flaps of a box or carton, said means embodying a pair of feed members, means for conducting a flap of said box or carton 60 therebetween, and elastic means adapted to contact with the sides of said flap after passing between said feed members for the purpose of removing superfluous adhesive therefrom.

65 5. In a device of the character described,

the combination of conveyer mechanism adapted to move along a predetermined path, means mounted thereon adapted to carry a box or carton having flaps adapted to be folded and sealed for the purpose of forming 70 a top or bottom therefor, mechanism interposed in the path of said conveyer adapted to apply an adhesive to a flap on a carton or box, said mechanism embodying a pair of adhesive feed members resting normally in 75 contact with each other and adapted to be separated by the passing of a box or carton flap therebetween and means adjacent to said feed members adapted to contact with the sides of flaps after passing therefrom for 80 the purpose of removing superfluous deposits of adhesive.

6. In a device of the character described, the combination of a main frame, a carton carrying mechanism mounted thereon adapted to travel in a predetermined path, means interposed in the path of said carton carrying mechanism adapted to apply adhesive to the flaps of cartons carried thereby, said means embodying a receptacle adapted to contain 90 adhesive, a pair of feed members movably mounted with relation to each other and adapted to be separated by the insertion of a carton flap therebetween, supply tubes or ducts leading from said reservoir to said feed 95 members, and means for actuating said carton carrying mechanism.

7. In a device of the character described, the combination with a box or carton carrying mechanism, of means interposed in the path thereof for folding the flaps of boxes or cartons carried thereby, and means adapted to apply a coating of adhesive to the flaps of said boxes or cartons, said means embodying a pair of feed members, one of said feed members being rigidly mounted and having an outlet orifice or slit on its upper surface, said outlet or slit being disposed at an angle to the line of movement of said conveyer and adapted to apply a coating of adhesive to the 105 under surface of a flap passed over the top thereof, the other said feed member being disposed above the said last mentioned member and movably mounted with respect thereto, and a feed slit or orifice in the lower 110 surface of said upper feed member extending at an angle to the line of forward movement of said carton carrying mechanism adapted to apply a coating of adhesive to the upper surface of a carton flap passed thereunder.

8. In a device of the character described, the combination with a box or carton conveyer adapted to move along a predetermined path, means interposed in the path of said conveyer, adapted to fold the flaps of 125 boxes or cartons carried thereby, means adapted to apply an adhesive to the flaps of boxes or cartons carried on said conveyer, said means embodying an upper feed member and a lower feed member, means for con- 130

ducting the flap of a box or carton therebetween, means adapted to support said upper feed member in movable relation to said lower feed member, and means for adjustably limiting the downward movement of said upper feed member in relation to said lower feed member.

9. In a device of the character described, the combination with a box or carton conveyer adapted to move along a predetermined path, of means interposed in the path of said conveyer adapted to fold the flaps of boxes or cartons carried thereby, and means adapted to apply an adhesive to both sides 15 of a flap of boxes or cartons carried by said conveyer.

10. In a device of the character described, the combination of a main frame, a carrier mounted thereon and adapted to move along 20 a predetermined path, box or carton carrying means mounted on said carrier, means interposed in the path of said carrier adapted to fold the front and rear end flaps of boxes or cartons carried thereby, means interposed in the path of said carrier adapted 25 to apply a coating of adhesive to one of the side flaps of boxes or cartons presented thereto by said carrier, a folding finger adjacent to the path of said carrier, said finger adapted to be actuated at predetermined intervals and to be carried forward with the carrier and thereby fold the said gummed side flaps inwardly and upon said folded front and rear end flaps, and means whereby said folding 30 finger is returned to normal when it has been carried to a predetermined position by the forward movement of the carrier.

11. In a device of the character described, the combination of a box or carton carrying 40 means adapted to move along a predetermined path, means interposed in the path of said carton carrying means adapted to apply a coating of adhesive to one of the side flaps of a box or carton, a folding finger mounted 45 adjacent to the path of said carrying means, said finger being slidably mounted to move in a direction approximately parallel to the path of movement of said carrying means, means on said carrying means adapted to 50 contact with said finger and to cause the same to move along the path of said carrying means during a predetermined portion of the forward advance thereof, means adjacent to said folding finger adapted to contact there- 55 with during the forward advance thereof and to cause the said finger to move inwardly, means adapted to disengage said folding finger from said carrying means, and means adapted to return said folding finger to normal.

12. In a device of the character described, the combination with a conveyer mechanism, box or carton carrying means carried thereby, a folding member slidably mounted 60 along the path of said conveyer mechanism

and adapted to be carried thereby at predetermined intervals during the forward advance of said conveyer mechanism, means on said conveyer mechanism adapted to contact with said folding member, means interposed in the path of forward movement of said folding member adapted to fold the same inwardly toward said conveyer mechanism, means adapted to disengage said folding member from said conveyer mechanism at a predetermined point in the forward advance of said folding member, means adapted to rock said folding member out of the path of said conveyer mechanism, and means for returning said folding member to normal.

13. In a machine of the class described, in combination, a main frame, a carrier, a support for boxes or cartons on the carrier, a standard on the carrier adjacent the carton or box support, a member mounted to slide longitudinally of the standard, a flap folding member pivotally mounted on said last mentioned member, and an elastic member interposed between said slidably mounted 90 member and the pivoted flap folding member.

14. In a device of the character described, the combination of a main frame, a carrier supported thereby and adapted to have movement thereon along a predetermined path, means mounted on said carrier adapted to receive boxes or cartons, means carried by said main frame adjacent to the path of movement of said carrier adapted to fold and gum flaps of boxes or cartons carried thereby, a carton support mounted on said carrier, an upright supporting member mounted on said carrier adjacent to said carton support, an elastically controlled folding and sealing member carried thereby, means carried by said main frame adjacent to the path of movement of said upright supporting member adapted to actuate said folding and sealing member, and means carried by 110 said main frame adapted to support the outer end of said upright support during the time that said actuating means is in contact with the mechanism carried by said support.

15. In a device of the character described, the combination of a conveyer mechanism, means carried thereby adapted to receive a paper box or carton having side flaps and end flaps adapted to be folded, means normally held at one side of the path of said conveyer and adapted to enter the path of the conveyer and to follow the carton with an accelerated movement for the purpose of folding the rear end flap, stationary folding means interposed in the path of said conveyer adapted to contact with forward end flap of the carton and to fold the same on the top of the said folded rear end flap, said stationary folding means operating also to fold one of the said side flaps outwardly and at an 130

angle to the adjacent side of said carton, means interposed in the path of said outwardly folded flap adapted to apply an adhesive to both sides of said flap, means adapted to fold said last mentioned flap inwardly and into contact with the surface of said folded front flap, means carried by said conveying means adapted to fold the remaining side flap inwardly and into firm contact 10 with said other folded side flap, said last mentioned means being adapted to retain its position in contact with said carton until the action of said adhesive has become effective, holding said flaps in folded position, and 15 means adapted to discharge said carton from said conveyer mechanism.

16. In a device of the character described, the combination of a main frame, a conveyer mechanism mounted thereon, means 20 for actuating said conveyer mechanism, means carried by said conveyer mechanism adapted to receive a paper box or carton and to hold same during the operation of folding and sealing the flaps thereof, means carried 25 by said main frame and interposed in the path of said conveyer mechanism adapted to fold the front and rear end flaps of the said carton or box inwardly and at an angle to sides of said carton or box, means interposed 30 in the path of said conveyer mechanism adapted to fold one of the side flaps of said box or carton outwardly, means for applying an adhesive to both sides of said outwardly folded side flap, means interposed 35 within the path of said conveyer mechanism adapted to fold said side flap inwardly and in contact with said folded front and rear end flaps, and means carried by said conveyer mechanism adapted to fold the remaining 40 side flap inwardly and upon the top of said folded side flap, said last mentioned means adapted to remain in contact with said folded flaps until said flaps are securely sealed.

17. In a device of the character described, 45 the combination of conveyer mechanism adapted to move along a predetermined path, embodying means for carrying boxes or cartons having side and end flaps adapted to be folded and sealed for the purpose of 50 forming tops or bottoms therefor, means interposed in the path of said conveyer mechanism adapted to apply an adhesive to one of the flaps of a box or carton, and means adapted to remove superfluous adhesive from 55 the said flap.

18. In a device of the character described, the combination of a carrier for boxes or cartons, means interposed in the path of said carrier adapted to apply an adhesive to one 60 of the flaps of a box or carton carried thereby, and means adapted to contact with the sides of said flap for the purpose of removing superfluous adhesive therefrom.

19. In a machine for folding and sealing 65 the ends of boxes, the combination of a main

frame, a carrier supported thereby and adapted to have movement along a predetermined path, a box support on the carrier a standard on the carrier adjacent to the box support carrying a pivoted flap folding member, means on the main frame adapted to actuate the pivoted flap folding member, and means on the main frame adapted to engage the said standard whereby it is supported during the time said actuating means on the 75 main frame is in contact with the said flap folding member.

20. In a device of the character described, the combination of a main frame, a carrier adapted to have movement along a predetermined path, means mounted on said carrier adapted to support boxes or cartons, an upright member mounted on said carrier adjacent to said carton support, a pivoted flap folding member carried by said upright 85 member, means on the main frame adapted to actuate said flap folding member, and means carried by said main frame adapted to support the outer end of the upright member.

21. In a device of the character described, 90 the combination of a main frame, a carrier mounted thereon, carton carrying and folding mechanism mounted on said carrier embodying a carton support, an upright member adjacent to said carton support, a discharge finger slidably mounted upon said upright support, and a pivoted flap folding member movably mounted on said upright support and adapted to contact with the top 95 of the carton support.

22. In a device of the character described, the combination of a main frame, a carrier mounted thereon, carton carrying and folding mechanism mounted on said carrier embodying a carton support, an upright member adjacent to said carton support, a discharge member slidably mounted upon said upright support, a pivoted flap folding member movably mounted on said upright support and adapted to contact with the top of 100 the carton support, and elastic means adapted to control said pivoted flap folding member.

23. In a device of the character described, 105 the combination of a main frame, a conveyer mechanism mounted thereon, means carried by said conveyer mechanism adapted to receive a box or carton and adapted to hold the same during the operation of folding and sealing the flaps thereof, means carried by 110 the main frame adapted to fold the front and rear end flaps of the carton or box inwardly, means interposed in the path of said conveyer mechanism adapted to fold one of the side flaps of a box or carton outwardly, and 115 means for applying an adhesive to both sides of said outwardly folded side flap.

24. In a device of the character described, 120 the combination of a main frame, a conveyer mechanism mounted thereon, means carried 125

by said conveyer mechanism adapted to receive a box or carton and adapted to hold the same during the operation of folding and sealing the flaps thereof, means carried by 5 the main frame adapted to fold the front and rear end flaps of the carton or box inwardly, means interposed in the path of said conveyer mechanism adapted to fold one of the side flaps of a box or carton outwardly, 10 means for applying an adhesive to both sides of said outwardly folded side flap, and a folding finger adapted to fold the above mentioned side flap inwardly.

25. In a device of the character described, 15 the combination of a main frame, a conveyer mechanism mounted thereon, means carried by said conveyer mechanism adapted to receive a box or carton and adapted to hold the same during the operation of folding and 20 sealing the flaps thereof, means carried by the main frame adapted to fold the front and rear end flaps of the carton or box inwardly,

means interposed in the path of said conveyer mechanism adapted to fold one of the side flaps of a box or carton outwardly, 25 means for applying an adhesive to both sides of said outwardly folded side flap, and means adapted to fold the said side flap inwardly embodying a member slidably mounted on the said main frame adapted to move in a 30 path approximately parallel to the path of movement of the conveyer mechanism and being provided with means by which the member is engaged by the conveyer mechanism.

35

In testimony whereof I have signed my name to this specification, in the presence of two subscribing witnesses, on this 22nd day of October A. D. 1906.

ROBERT Y. BRADSHAW.
